(57) **CLAIM**

The ornamental design for the solar light, as shown and described.

DESCRIPTION

FIG. 1 is a perspective view of a solar light, showing my new design.

FIG. 2 is a rear perspective view thereof.

FIG. 3 is a front view thereof.

FIG. 4 is a rear view thereof.

FIG. 5 is a left side end view thereof.

FIG. 6 is a right side end view thereof.

FIG. 7 is a top view thereof; and,

FIG. 8 is a bottom view thereof.

The broken lines on the drawings represent portions of the solar light that form no part of the claimed design.
